UNITED STATES PATENT OFFICE.

JAMES POWERS, OF NEW YORK, N. Y., ASSIGNOR TO POWERS ACCOUNTING MACHINE COMPANY, OF NEW YORK, N. Y., A CORPORATION OF DELAWARE.

RACK AND STAND FOR RECORD-CARDS.

1,250,220.

Specification of Letters Patent. Patented Dec. 18, 1917.

Application filed January 15, 1915. Serial No. 2,337.

To all whom it may concern:

Be it known that I, JAMES POWERS, a citizen of the United States, residing in New York, in the county of New York and State 5 of New York, have invented certain new and useful Improvements in Racks and Stands for Record-Cards, of which the following is a specification.

This invention relates to a rack and stand 10 for record cards such as record cards used in card perforating machines and the like.

One of the objects of this invention is to provide a rack and stand for record cards from which with facility the cards can be 15 removed either one at a time or a number at a time.

Another object of the invention is to provide a stand adapted to receive a portable card holding rack which may be removed 20 when its supply is exhausted to make room for another rack.

These and other features, capabilities and advantages of the invention will appear from the subjoined detailed description of 25 one specific embodiment thereof illustrated in the accompanying drawings in which—

Figure 1 is a perspective showing a card rack positioned on a stand ready for use.

Fig. 2 is a plan view of the same.

Fig. 3 is a detached elevational view of 30 one of the partitioning members disposed on the card rack showing its base member in section.

Fig. 4 is a fragmental section on the line 35 4—4 of Fig. 3.

Fig. 5 is a fragmental section on the line 5—5 of Fig. 3.

Fig. 6 is a fragmental perspective of a 40 portion of the stand with the card rack removed.

In the embodiment shown, there is provided a stand or supporting member 10 composed of two front standards 11, 11 parallel to one another and two rear standards 12, 12 which front standards 11 converge in their upward direction toward the two rear standards 12, 12, these standards being shown as composed of angle iron. The two front standards 11, 11 are spaced from and 45 connected to one another near their lower ends by an angle iron 13, the two rear standards spaced from and connected to one another near their lower ends by an angle iron 14, and each of the standards 11 spaced

from and connected to the rear standard 12 55 which is adjacent to it by an angle iron 15, which angle irons 15 are shown as having their upper horizontal portions 16, 16 disposed as resting on the upper surfaces of the horizontal portions 17, 18 of the angle 60 irons 13, 14 respectively.

The front standards 11 are shorter than the rear standards 12, and have their upper ends spaced from and connected to one another by a channel iron 19 forming a front 65 rail member, the ends of which channel iron 19 are connected to the rear standards 12 by angle irons 20, 20 or side rail members which slope slightly downward in their rearward direction, and have positioned on 70 them near their rear ends a supporting angle iron 21 or intermediate rail member which extends across from one to the other having one of its flanges 22 extending upwardly from the rear side of such angle iron 21 to 75 form a seat for the rear edge of the card rack to be supported thereon. The flange 22 lies in a plane in which are disposed the front surfaces of the upper ends 23, 23 of the rear standards 12, 12, and the ends of 80 such angle iron 21 are connected to such upper ends 23, 23 by bracing members 24. The upper ends 23, 23 are furthermore connected to one another by the longitudinally 85 extending angle iron 25 or rear rail member.

By this arrangement, the seat on the supporting member 10 is formed by the upper surface 26 of the channel iron 19, the two surfaces of the angle iron 21 and the front surfaces of the longitudinally extending 90 angle iron 25, which seat it will be seen is of the rearwardly sloping kind having the front end of the base portion of such seat at a higher level than its rear end, and its rear supporting portion in a plane that is 95 substantially at right angles to the plane in which the base portion is disposed.

The card rack comprises essentially a base member 27 preferably composed of metal, the rear wall member 28 preferably composed of metal and suitably secured to and disposed at right angles to the base member 27, and two end wall members 29, 29, secured to the adjacent ends of the base member 27 and rear wall member 28 by flanges 100 37 and 38 respectively. Disposed between these end members 29 and parallel to such end members are secured a plurality of par-

partitioning members 30 which are likewise secured to the base member 27 and rear wall member 28 similar to the end wall members 29 by flanges 39 and 40 respectively. These 5 partitioning members 30 may be spaced from the end wall members 28 and from one another at equal distances, as illustrated, to form pockets for the cards, when the cards to be used are all of a like width. The outer 10 free edges 31 of the end wall members 28 and partitioning members 30 may preferably be formed into beads as shown and have front portions 32 parallel to the rear wall member 28, and upper portions 33 of curved 15 conformation extending from the front portions 32 to the rear wall member 28. These end wall members 29 and partitioning members 30 are preferably composed of sheet metal. To facilitate the removal of the 20 cards from the stalls formed between the partitioning members 30 and end wall members 29, so that they will not be obstructed in their movement by the beads formed at the free edges of such partitioning members 25 30 and end wall members 29, each of the partitioning members 30 is provided with two offset members 34, preferably composed of wood, one on each of the two faces of said partitioning members 30 and disposed along 30 the middle longitudinal portions of said partitioning members parallel to the rear wall member 28. These wooden offset members 34 are secured to the partitioning members 30 by means of rivets 42 that pass from 35 one wooden offset member 34, through a partitioning member 30, then through the other wooden offset portion 34 terminating on the outer sides of said offset portions 34. The inner faces of the end wall members 29 are provided with offset portions 35 similarly disposed.

For the purpose of permitting the transportation of said card rack from place to place, handle members 36 are provided one 45 on the outer face of each of said end wall members 29, which handle members are of the usual pivotal construction which drop down into suspended position alongside of the wall to which they are attached.

50 When the card rack is positioned on the stand 10, its rear wall member 28 will have its lower end disposed against the upwardly extending flange 22, its intermediate longitudinal portion resting against the angle iron 25, and the base member 27 of such card rack will rest on the upper horizontal portion 26 of the channel iron 19 and the horizontal portion 41 of the angle iron 21. Since the seat on the stand 10 is of the sloping kind, it will be seen that the card rack 55 when disposed thereon will slope rearwardly.

It is obvious that various changes and modifications may be made to the details of construction without departing from the 60 general spirit of the invention.

I claim:

1. In a device of the class described, a card rack having a base member, a rear wall connected to said base member, two end wall members secured to and at the ends of said 70 base member and rear wall, partitioning members secured to said base member and rear wall between said end wall members and suitably spaced apart from one another and from said end wall members to form 75 card receiving pockets, said end wall members and partitioning members being composed of metal, a bead formed on the free edges of each of said end wall members and partitioning members, and outstanding wooden members disposed longitudinally on each of the faces of said partitioning members and parallel to said rear wall to prevent the obstruction of the cards by said beads when being removed.

2. In a device of the class described, a card rack having a base member, a rear wall connected to said base member, two end wall members secured to said base member and rear wall between said end wall members and suitably spaced apart from one another and from said end wall members to form 90 card receiving pockets, said end wall members and partitioning members being composed of metal, a bead formed on the free edges of each of said end wall members and partitioning members, outstanding wooden members disposed longitudinally on each 95 of the faces of said partitioning members and parallel to said rear wall to prevent the obstruction of the cards by said beads when being removed, and rivets for securing said 100 wooden members to said partitioning members, said rivets extending from the outside of one wooden member through a partitioning member and out of the other wooden member and terminating on the outer faces 105 of said wooden members.

3. In a device of the class described, a card-rack having a base-member, a rear-wall connected to said base-member, two end wall members secured to and at the ends of said 110 base members and rear wall, partitioning members secured to said base-member and rear wall between said end wall-members and suitably spaced apart from one another and from said end wall members to form 115 card receiving pockets, said end wall members and partitioning members being composed of metal, a bead formed on the free edges of said end wall members and partitioning members; outstanding wooden members disposed longitudinally on each of the faces of said partitioning members and 120 parallel to said rear wall to prevent the obstruction of the cards by said beads when being removed; rivets for securing said 125 wooden members to said partitioning members to said partitioning mem- 130

bers, said rivets extending from the outside of one wooden member through a partitioning member and out of the other wooden member and terminating on the outer faces 5 of said wooden members; and a supporting stand for the card-rack having a seat comprising a frame, having a front rail member at the upper end of said frame, two side rails sloping downward in a rearward direction 10 from said front rail member, an intermediate rail member positioned on said side rail-members, and a rear rail member disposed rearwardly and above said intermediate rail-member so as to form a sloping seat, whereby the card-rack is tilted toward the 15 rear.

JAMES POWERS.
